(57) CLAIM

The ornamental design for a lipstick container, substantially as shown and described.

DESCRIPTION

FIG. 1 is a front perspective view of a lipstick container in accordance with the invention;

FIG. 2 is a side elevational view thereof, both sides being identical;

FIG. 3 is an end view thereof from the left-hand end in FIG. 2;

FIG. 4 is an end view thereof from the right-hand end in FIG. 2;

FIG. 5 is a top plan view shown with the tassel in an alternate, more closely bundled configuration; and,

FIG. 6 is a bottom plan view showing the tassel in a fully bundled configuration.
